UNITED STATES PATENT OFFICE

WILLIAM C. HAYMAN, OF SCHENECTADY, NEW YORK, ASSIGNOR TO GENERAL ELECTRIC COMPANY, A CORPORATION OF NEW YORK

HIGH-TENSION CABLE

Application filed December 14, 1928. Serial No. 325,991.

The present invention relates to high tension cables designed primarily for use in underground conduits, although it is not to be construed as necessarily limited to such use.

It is the practice at the present time to provide these cables with electrostatic shields to prevent corona effect which are located between the outer surface of the conductor insulation and the enclosing metal sheath, which is commonly made of lead. These shields are made of very thin metal in the form of wrapped-on ribbon, and are easily torn or stretched, or both, in the process of leading the cable. The ribbons are perforated at suitably spaced intervals to permit the insulating fluid to freely pass through from one side to the other so as insure complete impregnation of the paper or other insulation. These perforations further weaken the ribbon and increase the manufacturing difficulties. It is also the practice with multiple conductor cables, especially of the shielded type to provide an additional wrapping of steel tape in the form of a band, which is wrapped on over the shielding ribbon.

In order that the metal ribbon may perform its function as a shield, it must be in electrical communication, and preferably over a portion of each and every turn or wrap, with the lead sheath. Where a metal band is provided in addition, electrical contact must be maintained from ribbon to the band and from it to the sheath.

To guard against injury to the ribbon or band, or both, as the case may be, in the manufacturing operation it is the practice to wind over the ribbon or band a temporary layer of paper and also a longitudinally extending cord, termed a "rip cord", by means of which the outer temporary layer of paper may be ripped off at some point adjacent to the entrance of the cable into the lead press. Such an arrangement while generally satisfactory in results requires an operator whose job it is to see that all of the outside paper covering is removed before the cable is leaded, and also to see that paper does not accumulate and get into the press. Obviously, this extra

operation increases the cost of the cable and is generally objectionable.

In accordance with my invention an arrangement of parts is provided whereby the use of temporary and removable external wrapper of paper to hold the ribbon or band in firm contact with the insulation on the conductor to prevent injury is avoided and in this manner am able to dispense with one operation and one operator in the manufacture of cable of the character described. I am also able to ensure the proper seating and binding of the ribbon or band in place.

For a consideration of what I believe to be novel and my invention, attention is directed to the accompanying description and claims appended thereto.

In the drawing which is illustrative of my invention, Figure 1 is a longitudinal section, partly in elevation, of a piece of single conductor cable; Figure 2 is an end view of the same; Figure 3 is a longitudinal section, partly in elevation, of a piece of three-conductor cable; Figure 4 is an end view of the same; and Figure 5 is a diagrammatic illustration showing the way the metal ribbon or band or both are arranged in over-lapping relation with the paper tape or strip.

6 indicates a bundle of individual copper conductors which are stranded in any suitable manner to form a cable. Surrounding the conductor and tightly wrapped thereon are concentric turns or layers of paper 7, said paper being wound spirally as is the common practice. The shielding ribbon 8, 25 may be wound directly on the insulation or there may be interposed between the two an extra layer of a good grade of tough paper to form a bed 9, for the ribbon, and which is somewhat elastic. Either directly on the conductor insulation or on the bed, when the latter is provided, there is simultaneously wound by machine to give the necessary tension and uniformity, the perforated shielding ribbon 8, and a strip of good tough paper 10. The arrangement is such that approximately one-half of the paper strip overlies approximately one-half of the outer surface of one turn of the shielding ribbon and the remainder of the strip of paper underlies 100

approximately one-half of the adjacent turn or wrap of the shielding ribbon. The adjacent turns or wraps of the ribbon are separated at their edges by approximately the thickness of the paper where it passes from the underside of one turn to the outer surface of the adjacent turn. This abutting arrangement is the best, although, in some cases, it will be satisfactory to have the edges of the ribbon separated by a somewhat greater amount, provided that the electrostatic stress on the impregnating fluid between the edges or elsewhere is not thereby made too high.

As a result of the overlapping arrangement, one part of each turn of the paper strip is bound down by a metal ribbon and the other part binds down the adjacent turn of said metal ribbon. The paper is of such a width and so positioned that the metal ribbon is exposed between turns as indicated at 11, Fig. 1 to make electrical contact or ground with the sheath 12. The paper should be as thin as possible, consistent with the strength required. In most, if not all cases, it will be satisfactory to use the same kind of paper that is used for the outside layers on the conductor.

As before stated, the metal ribbon is thin, being, for example, of the order of from three to five mils in thickness. After the ribbon and paper tape are tightly wound in place, it will be found that the peripheral surface is smooth and flat. This is due to the fact that the exposed part of the thin metal ribbon is slightly stretched in the winding operation, and to the fact that the paper is somewhat yielding, which permits the ribbon to sink into it to a limited extent. In feeding the cable into the press, which covers the cable with lead as indicated at 12, it should be done in such manner that the paper covers the entering edges of the successive turns of the metal ribbon thereby protecting them from injury.

In Figure 5 is illustrated diagrammatically the arrangement of the metal ribbon 8 and the wound-on strip of insulation 10. It will be observed that one part of the strip is under the ribbon and extends through the small space between edges of adjacent turns of the ribbon and covers a part of the adjacent turn. In practice, the space between edges of the metal ribbon is made equal to the thickness of the paper. 7 indicates the insulation on the conductor and 7^a indicates a paper wrapping to form a bed when such a bed is found to be desirable.

Referring now to Figures 3 and 4, which indicate a suitable arrangement for a multiple conductor cable, 13 indicates the copper or other conductors which are covered by wound-on insulation 14 of which paper is a good example. The peripheral surface of each conductor covering is wound with a ribbon 15, to form an electrostatic shield, which,

to attain the best results, is perforated in order to permit the fluid insulation to freely penetrate the paper. The ribbons on the several conductors, when assembled as shown, are in contact one with the other. The space 70 in the center between the conductor coverings is filled by a suitable filler 16, and the spaces between the outer portions of the conductor coverings and the peripheral portions contain fillers 17 made of paper, jute or other 75 suitable material. In order to prevent the conductors from spreading due to any cause, as, for example, in bending and later straightening the cable, which would have the effect of stretching the lead covering and thereby 80 causing voids, the conductors after being assembled to form a cable in the usual manner are wrapped with a thin metal covering which to distinguish it from the other metal coverings will be referred to as a band 20. 85 This band may be made of thin steel or equivalent metal having the necessary tensile strength to firmly hold the individual conductors in their assembled relation and prevent spreading. This band and a strip of 90 paper 21 are wound simultaneously over the conductors in the manner described in connection with the perforated ribbon 8 of Fig. 1. That is to say each turn of the paper tape 95 is partly covered by one turn of the band, the other part of the tape covering a part of the turn of the adjacent wrapping of the band. In winding, the shield 15 is wound on say with a right-hand spiral, while the steel band is wound in a left-hand spiral. In other words, the two metal coverings cross each other instead of occupying similar positions. This facilitates the several operations, and at the same time results in a smoother and better finished cable. After the band is applied, the cable is fed through a press and given a lead covering 22. When this is done 100 all of the shields as well as the binding band are in electrical communication and are grounded to the sheath.

The insulation on the cable illustrated is impregnated with a suitable insulating compound and is generally known as a solid cable, but the invention is equally applicable to cables of other types in which definite channels are provided for oil or other insulation as for example by omitting some of the fillers.

I have referred to the electrostatic shield for simplicity as being made of metal, but it is to be understood that in this designation I aim to include materials which have only a metalized surface and not one composed wholly of metal.

I have referred to lead as the protective or outside covering or sheath and by this term I include all coverings in which lead is the principal element, although it may be alloyed with other materials to give it greater 125 strength.

What I claim as new and desire to secure by Letters Patent of the United States, is:

1. A cable comprising a conductor, insulation thereon, a spirally wrapped ribbon of metal, a protective strip which underlies a portion of each turn of the ribbon and also overlies a portion of the peripheral surface of the turns of said ribbon, and a protective metal covering which is in electrical communication with said metallic ribbon.

2. A cable comprising a conductor, insulation thereon, a thin ribbon of metal which is spirally wound thereon, non-metallic means which overlies one edge and a portion of each turn of said metal ribbon, and underlies a portion of an adjacent turn, and a protective metal covering which is in electrical communication with said metallic ribbon.

3. A cable comprising a conductor, insulation thereon, a covering comprising a thin ribbon of metal wound thereon, the turns being positioned side by side, a thin strip of insulation which separates the edges of the turns of the metal strip by extending through the space between them, one part of the insulation underlying one turn of the metal and the other portion partly overlying an adjacent turn, and a protective metal covering which is in electrical communication with said ribbon.

4. A cable comprising a conductor, insulation thereon, a covering comprising a thin strip of perforated metal wound thereon, a thin strip of paper which partly underlies the turns of the metal strip and partly overlies them by extending between the edges of adjacent turns, said paper forming a yielding bed for the metal so that the exterior presents a smooth surface, and a protecting covering made of lead which is in electrical communication with the turns of the strip.

5. A cable comprising conductors, insulation thereon, an electrostatic shield comprising a spirally wound metallic ribbon, insulating material which also is spirally wound, said material being partly under one turn of the ribbon and partly over an adjacent turn, a metal band to prevent the conductors from spreading, the ribbon and band being in electrical contact, and a metal covering for the cable which is in electrical contact with the band.

6. A cable comprising conductors, electrostatic shields for the conductors, a spirally wrapped band which prevents the conductors from spreading, a strip of paper also spirally wound, each turn of which underlies a part of one turn of the band and overlies a part of an adjacent turn, and a metallic sheath for the whole which snugly fits the band and is in electrical contact therewith.

7. A cable comprising conductors, spirally wound perforated metallic ribbon thereon, spirally wrapped insulation which underlies a part of each turn of the ribbon and overlies

a part of each adjacent turn, a band to prevent the conductors from spreading which is also spirally wrapped over the ribbon and its insulation, a spirally wrapped member which underlies a part of each turn of the band and overlies a part of each adjacent turn, said ribbon and band being in electrical contact, and a lead sheath which is in electrical contact with the band.

8. A cable comprising conductors, insulation therefor, an electrostatic shield for each conductor, a band which is spirally wrapped around the conductors to prevent them from spreading, insulating material which partly underlies and partly overlies the several turns of the shields and band, said band being in electrical communication with all of the shields, and a protective lead covering.

9. A cable comprising conductors, insulation therefor, an electrostatic shield which is spirally wrapped around each of the assembled conductors, a metal band to prevent the conductors from spreading and which is in electrical contact with the shields, said band being spirally wrapped around the shields, but in the opposite direction, so that the turns of the shields and the band cross each other, means to hold down one edge of each turn of the band, and a protective lead covering which is in electrical contact with the band.

In witness whereof, I have hereunto set my hand this 13th day of December, 1928.

WILLIAM C. HAYMAN.

DISCLAIMER

1,751,403.—*William C. Hayman*, Schenectady, N. Y. HIGH-TENSION CABLE. Patent dated March 18, 1930. Disclaimer filed February 10, 1931, by the assignee, *General Electric Company*.

Hereby disclaims and withdraws that portion of the specification in which it is stated that the electrostatic shield in accordance with the invention of the patent may consist of a material which has only a metallized surface, to wit, page 2, lines 119 to 124, inclusive, as follows:

"I have referred to the electrostatic shield for simplicity as being made of metal, but it is to be understood that in this designation I aim to include materials which have only a metallized surface and not one composed wholly of metal."

and General Electric Company hereby disclaims the cable which is set forth in the claims of said patent except when the ribbon or strip constituting the electrostatic shield is a metal ribbon or strip of the order of three to five mils in thickness.
